7359X

A. Hathaway.
Ruling Mach.

No. Patented Dec. 31, 1832.

7359X

Dec. 31, 1852

1903

Alfred Hathaway, of Dray Massachusetts,

Letters Patent.

The schedule referred to in these Letters Patent, and making part of the same, containing a description in the words of the said Alfred Hathaway himself of his improvement in the machine for ruling paper.

To all whom it may concern:

Know ye that I, Alfred Hathaway, of Dray in the State of Massachusetts have invented, contrived, & applied to use a new & useful improvement in the machinery for ruling paper which I have named, "Hathaway's Improved Ruling Machine" by which both sides of the paper are ruled at one operation. Said machine is specified and described as follows: Fig. (not drawn being had to the annexed drawing as part of this specification) Fig. A. is a cylinder say 36 inches in diameter with a flange or guide, half an inch high on either end as may suit the operator; this flange or guide serves as a guide to lay the paper on the whole made of hard iron & turned true; this cylinder is covered with a wooden cloth & runs on friction rollers T.T.; a cylinder of larger size would probably be more economical. B. is a balance wheel, of size & weight sufficient to keep up the motion of cylinder A. It is attached to a shaft which runs across the top of the frame, with a crank on both ends (two balance wheels in one end and of the shaft would probably be a practised improvement). C. (Fig. 3) is another cylinder (which should also be of friction) if the machine is to be used for ruling on both sides at once, from one side only wood with arrows) deep & sufficiently deep to receive the waste which binds the paper to cylinder A. & carry the same from cylinder A to cylinder C. to be covered also with a wooden cloth, & neatly fitted in the cover, so as to bring

The curved surface of the cylinder or roller *A* should be
about 2000 yards on this cylinder, & so arranged as to bind & carry
the different edges of paper, with a running cord as shown, which
seams should match with those on rollers *B* & *C*. (see figs.)
The size of the cylinder, if from 5 to 10 inches, will be sufficiently
large for the paper to turn on; & as the points of the pins stick
out of the cylinder, the size does not materially affect the
winding. ... *D* (see fig 1) are pulleys on the end of the shaft of cylinder
C, which runs loose on another shaft with a dog in the pulley back
wheel on the shaft to prevent the machine from starting the wrong
way. ... *E* (fig 1) pulley to increase the motion of the balance wheel
by which the motion of the cylinders is regulated. The outside
pulley to run with pulley *D*, the inner pulley are smaller to run
with pulley *D*. pulleys *B* are all connected & run on a third shaft
set to the frame. *F* (fig 1) is a pulley on the end of the balance wheel
shaft & runs with the large pulley *E*. *G* (fig 1) is a small iron wheel
on which the candlestone and is about $1\frac{1}{2}$ inch. in diameter
scored as near together as possible, for the purpose of accom-
modating the ends when moved to clear the pens. This roller hangs
about 10 of an inch from cylinder *C*. ... *G* (fig 2) is a small iron
roller about the size of roller *G*. I used like that, to bring the
cords over cylinder *C*, on the surface, between the two rollers in cylinder
C. ... *H* (fig 2) wooden rollers to keep the cords from the cylinder
on their return motion and to carry the paper to the buffer *E*.
I (fig 1) is a frame in which the pens are set for winding; it consists
of two bars of brass from half to three quarters of an inch square
with a groove in the front of each bar, with ends to keep the pens
permanent; the groove in the back bar receives a tip on the back of the lower
cylinder for the ink; the groove in the front bar receives a hook on a dog
the other end of which hooks into the front of the cylinder for ink; a peg
of a blunt iron that's the dog's bearing against the bar opposite the back
which hooks into the front of the front bar in the same is helpful,
if you think me to do it in a good place. ... *J* (fig 1) is a sharp
iron

be without (i.e. outside of) the books which book is the groove in
the front bar, the latter to coincide with the front of the cylinder in
order to bring the points of the pens in the different cylinders to bear
with equal pressure on the paper when writing. The bars or cylinders
or canisters themselves, are made of brass or copper, about half an inch
deep, twice or nearly twice wide (the length in proportion to the
number of pens, & the manner of their arrangement) with a lip on
the top of the back of the cylinder to fit in the groove in the back bar
of the frame to a groove in the front of the cylinder to receive the
book on the clasp with to be behind the front of the cylinder, extending
and from the cylinder about half an inch on a straight line with
the bottom of cylinder, the tubes are flat & stand upright about
three sixteenths of an inch deep, & open at the top for the purpose
of cleansing them. They are made of brass. The pens are flat tubes
open at the top, standing upright, and are sufficiently wide to fill
the ends of the tubes & are made one volume into them inclining several
ways to as to bring the points to bear on the top of the cylinders
while the cylinders being a sufficient distance above the cylinders to give
the cords a free operation under them. & the same as I. — **J** (fig. 1) is a
lever attached to the frame, to give the pressure on the points of the
pens & is made fast at one end, having a spring at the other
L is a spring attached to the end of lever. **M** is a rock to enable the
spring to in, in order to get the pressure on the points of the pens.
N (fig. 10) is a table for the paper. **O** (fig. 10) treadle which hangs at the
back posts of the frame. **P** (fig. 10) the foot board which is made
fast to the sides of the treadle, & by means of which the machine
is worked. **Q** (fig. 10) The pilman or song which runs from about
the middle of the treadle to the end. & the end made to ray to
accommodate the motion of the feet. — **R**, **S**, friction rollers. **R** is on edge
stands upright to the sides of the frame and bearing lightly against the
ends of the shaft of the cylinder in its place. — **S**, a small iron roller
about half the size of the iron roller **R** is used to roll with it to
keep the wood round the cylinder a pen & prevent it in order

to give the paper a free operation, it is a perforate support which is hinged at B, and varied by screws to alter the position of the center as necessity may require... a fig 11 is for the same purpose with X, but of a different form, for the hinged supports to alter his made fast to the frame by a set screw with a slot in the bone to permit of moving to accommodate the position of the perch (fig 9) is a guide on the side of the frame in which one of the treadles operates to keep the foot motion steady. (fig 9) is a round bolt or band (running in order with the two round round cylinders C and round cylinder C. on the surface) sufficiently strained to give cylinder C the same motion with cylinder C... a round bolt or bands by means of which the foot motion is connected with & communicated to the Machine... (fig 11) is a screw by which the position of the perch is regulated. (fig 11) is the hopper which receives the paper after it is ruled. Figures 1 are a set of cords running from the small iron roller C. to cylinder C. to bind the paper to cylinder C. & carry it to cylinder C... Figures 2 are a set of cords to bind the paper to cylinder C. being to roller B on the back of the frame... Figures 3 are a set of cords which carry the paper from roller E to the hopper S. The specific improvements which I claim as my invention in the aforesaid specification are, 1st. Ruling both sides of paper during operation or one side only... 2d. The application of the motion to the Machine & the general arrangement of the machine & the placing of it by yourself... 3d. The position & construction of the frame & the application of the perch to the top of the cylinder.

In testimony of which I the said Alfred Whitney have hereunto set my name at Providence in the State of Rhode Island this twelfth day of Sept A.D. 1830.
